INVENTOR.

Paul S. Heller
BY

ATTORNEY.

UNITED STATES PATENT OFFICE.

JOHN WM. HELLER, OF BUENA, NEW JERSEY.

FOLDING RULE.

1,394,088.

Specification of Letters Patent.

Patented Oct. 18, 1921.

Application filed April 6, 1921. Serial No. 459,046.

To all whom it may concern:

Be it known that I, JOHN WM. HELLER, citizen of the United States, residing at Buena, in the county of Cumberland and 5 State of New Jersey, have invented certain new and useful Improvements in Folding Rules, of which the following is a specification.

The present invention has reference to 10 new and useful improvements in folding rules and relates more specifically to a combined foot rule, try square, bevel protractor and divider or compasses, and the particular object of the invention is the provision of an 15 instrument of this character which is cheap in manufacture, reliable in operation, and which is obtained by simply articulating a link bar to two hingedly adjoining rule members or sections, means being provided 20 for making this articulation temporarily rigid in any desired relative angular displacement of the link bar connected rule sections.

My invention will best be understood when 25 described in connection with the accompanying drawing, in which Figure 1 represents a plan view of the combination tool in its simplest form, in folded-up position, and Fig. 2 is a plan view of a four-section rule 30 in use when establishing an angle of 90°.

For the purposes of my invention, I preferably use the ordinary 2-foot rule, comprising 35 four members or sections, of which in Fig. 2 only the sections 1, 2 and 3 are shown, hinged together in the conventional manner to fold into a short compass for convenience in carrying. The right extremity of section 2 is hinged to section 1 by a hinge 4 and its left extremity is hinged to an underlying 40 section, invisible in the drawing, by a hinge 5 operating perpendicularly to the hinge 4, and this invisible section in turn is connected at its other end to the section 3 by a hinge identical to, and in axial alinement 45 with the hinge 4, as well known in the art.

An elongated flat link bar 6, preferably 50 of sheet metal, having a central elongated slot 7 therein slightly curved-out at one end, as at 8, is stationarily fulcrumed to the narrow side of the rule member 1 in suitable manner, for instance by a headed pin 9, and is shiftably articulated to the respective narrow side of the hingedly adjoining rule section 2 by means of a suitable clamping member, for instance a screw pin and nut, or, as 55 shown, a knurled thumb screw 10 threading

into the section and whose shank moves freely in said link slot. The link bar is marked with indicia 11 referring to different angles, such as 30°, 45°, 90° and so on, for 60 readily adjusting the parts to the desired angles.

For setting the device to a certain angle, for instance as shown to 90°, the free ends of the rule sections 1 and 2 are drawn apart 65 until the shank of the set screw 10 registers with the 90° mark on the slotted link bar, when by tightening the screw 10 the parts are immovably held, the two sections including between them an angle of 90°. I 70 may also provide positioning marks 14 on the section 2 for exact registry with the angle indicia 11 on the link bar.

In laying out or establishing angles on certain work in the case of a four-section rule it will be found helpful to keep the rule section 3 folded flat against the companion section (the one not shown in the drawing) and this latter section parallelly underneath section 2, to steady the device on the work 80 piece.

Steel points 12 and 13 respectively extend from the free ends of the rule sections 1 and 2, which allows of the device being used as a divider or a pair of compasses. 85

In folded-up position of the tool, the screw shank engages in the angularly directed short slot branch 8, as shown in Fig. 1.

In Fig. 2, by way of example, the dash-dot lines diagrammatically indicate the position of the parts when laying out an angle of 135°, and the dash-dash lines when laying out an angle of 45°.

This combination tool will be found very 95 convenient and valuable in a variety of ways in the work shop.

What I claim as new and desire to secure by Letters Patent is:—

1. In a device of the character set forth, 100 in combination with a conventional foldable foot rule, presenting hinged sections, an elongated flat link bar having a central elongated slot therein, means associated with one of said rule sections for stationarily fulcruming said link bar near its one extremity to this rule section, and means associated with the hingedly adjoining rule section for shiftably articulating and temporarily fixing said link bar to this second said rule 105 section.

2. In a device of the character set forth,

in combination with a conventional foot rule
of the foldable section type, a flat link bar
having marked thereon angle indicia and
presenting a central elongated terminally
5 curved-out slot, means for stationarily pivot-
ing said link bar to a rule section, means
for shiftably articulating said link bar to
the hingedly adjoining rule section and for
temporarily fixing the parts in their rela-
10 tive shifted position, comprising clamping

means associated with the second said rule
section and adapted to releasably clamp-
ingly coöperate with said link bar, the sec-
ond said rule section bearing setting marks
adapted for registry with said angle indicia,
and pin points extending from the free outer
end faces of the said two hingedly adjoin-
ing rule sections.

In testimony whereof I affix my signature.
JOHN WM. HELLER.
